CLAIM

The ornamental design for a firearm suppressor, as shown and described.

DESCRIPTION

FIG. 1 is a rear, top, left side perspective view of a firearm suppressor according to the present disclosure.

FIG. 2 is a front, top, left side perspective view of the firearm suppressor of FIG. 1.

FIG. 3 is a front view of the firearm suppressor of FIG. 1.

FIG. 4 is a back view of the firearm suppressor of FIG. 1; and,

FIG. 5 is a side view of the firearm suppressor of FIG. 1. The broken lines in the Figures and the unshaded areas within the broken lines illustrate portions of the firearm suppressor that form no part of the claimed design.

1 Claim, 3 Drawing Sheets
